Attorneys.

UNITED STATES PATENT OFFICE.

ADELARD FARLAND, OF PROVIDENCE, RHODE ISLAND.

KNITTING MACHINE.

Application filed August 2, 1922. Serial No. 579,167.

To all whom it may concern:

Be it known that I, ADELARD FARLAND, a citizen of the United States, residing at Providence, county of Providence, State of Rhode Island, have invented certain new and useful Improvements in Knitting Machines, of which the following is a specification.

This invention relates to improvements in knitting-machines and particularly to machines of circular type for knitting tubular fabrics.

One object of the invention is to provide an improved holder for the burr-wheels and other attachments or implements employed with the knitting-needles.

Another object of the invention is to provide a combination holder for a plurality of the attachments which will economize space and allow a closer setting of the knitting elements around the machine.

Another object of the invention is to provide an improved presser-bar for the burr-wheel which will be simpler and more compact in construction and arrangement and more efficient for the purpose intended.

Another and most important object of the invention is to provide an improved means for mounting the implements or appliances of the knitting mechanism so that they may be conveniently adjusted in relation to the knitting-needles, while also permitting a close setting of a plurality of the appliances in relation to each other, and rendering them more convenient to remove and replace with attachments of other types in accordance with varying requirements for different classes of work.

Still further objects of the improvement are set forth in the following specification which describes a preferred embodiment of the invention as illustrated by the accompanying drawings. In the drawings:

Fig. 1 is a part sectional view of a portion of a circular knitting-machine showing my improved attachment applied thereto; and

Fig. 2 is a detailed view of the attachment.

Referring to Fig. 1, the reference numeral 2 designates the fixed horizontal bed-plate of the machine and 3 the rotating needle-cylinder or head which carries the row of bearded needles 4 on its circumference. It will be understood that in the present type of machine the needles 4 are held fixedly to the periphery of the cylinder or

head 3 by the clamp-ring segments 5 so that they revolve with the head but without movement thereon. The tubular fabric, represented at F in Fig. 1, is formed by the well-known method of chain-looping the yarns on the needles 4 through the cooperation therewith of a set of burr-wheels and other appliances or attachments of various types. In the present drawings I have shown one attachment only comprising a combination holder or support for carrying one of the knitting-burrs 6 and the presser-foot 7. It is to be understood, however, that the improved form of holder herein illustrated may be adapted for carrying any or all of the various burrs of the set, such as the "loop-wheel", "sinker-wheel", "presser-wheel", "landing-wheel", "stripping" or "knocking-over wheel", the curved "cloth presser" or any other attachment or appliance as employed in conjunction therewith. The means for mounting the holders on the bed-plate of the machine is also common to all of the various attachments to be used and constitutes an important feature of the invention.

My improved anchoring or attaching means for the appliance-holders comprises a raised ring or annular track 10 which is preferably supported on the bed-plate 2 in spaced relation to the periphery of the head or needle-cylinder 3. The track or annulus 10 may be constructed in the form of a continuous hoop or ring or may be made up of a plurality of arcuate segments of substantially rectangular shape in cross-section seated against the flat top of the bed-plate 2. The ring or track 10 is fastened in place by means of screws 11 threaded into bores in the bed-plate 2, the heads of the screws 11 being countersunk into the top of the ring to provide a smooth, unbroken surface along its upper face.

The holders 12 for the various attachments of the machine comprise essentially a circular base or hub 15 which is provided with an arcuate slot 16 on its under side to adapt it to be placed over the track or ring 10 with its bottom seated on the bed-plate 2; and a cylindrical post or standard 18 which rises from the top of the hub. The hub or base 15 may be slid along the track 10 to adjust the holder 12 in position circumferentially of the axis of the machine, and suitable means, such as the set-screw 19, are employed for binding it against the

track to secure the holder in position. The post or standard 18 may be constructed integral with the hub 15, but as herein shown, it is preferably made from a separate rod 5 which has its lower end seated in a bore 20 in the hub and secured in place by a set-screw 21. The post 18 is adapted to support a plurality of arms for carrying the burrs or other appliances which cooperate 10 with the needles of the machine, two of these arms being shown in Fig. 1.

The upper arm 25 carries a relatively fixed presser-member of the usual type which reaches down inside of the row of needles 4 15 with its curved foot 7 pressing against the lower edge of the fabric F to hold the stitches depressed on the needles. The arm 25 preferably consists of two parts, a main section 28 having a split hub 29 encircling 20 the post 18 and clamped thereto by a set-screw 30; and a cylindrical extension 31 which slides in a bore in the main arm 28. The presser-foot 7 projects downwardly from the end of the extension 31 and may be 25 adjusted radially of the axis of the machine by telescoping the extension 31 within the main arm 28. A set-screw 32 or other suitable means is employed for binding the extension 31 in the arm 28 to secure the 30 presser-foot in its position of adjustment.

The lower arm 35 which is shown as carrying the burr-wheel 6 is provided with a hub 37 bored to receive the post 18. The arm 35 projects radially outward away from the 35 axis of the machine and a set-screw 36 holds it from sliding on the post 18. Referring particularly to Fig. 2, the inner end of the arm 35 is provided with a vertical slot 38, while the outwardly projecting portion of 40 the arm is chambered with an axial bore 39. At the outer extremity of the arm 35 the bore 39 is threaded to receive the barrel of a thimble 40 which is formed with a shoulder 41 adapted to seat against the end of the 45 arm. A rod 42 has its main portion flattened off on the sides at 43 to adapt it to be inserted through the slot 38 in the end of the arm 35 and to pass through an elongated slot 44 in the post or standard 18 on which 50 the arm 35 is mounted. At its inner end the rod 42 is provided with a reduced portion 45 carrying a bearing-member 46 secured thereon by a set-screw 47. The bearing-member 46 carries a spindle 48 on which is journaled 55 the burr-wheel 6.

The rod 42 is also reduced in diameter at its opposite end to provide an elongated spindle 50 which projects through the axial bore in the thimble 40, see Fig. 1. A helical 60 spring 51 surrounds the spindle 50 within the chambered bore 39 of the arm 35 and, acting between the end of the thimble 40 and a shoulder 52 on the rod 42, tends to urge 65 the rod to the right as viewed in Fig. 1. A 68 nut 53 engaging threads 54 on the outer ex-

tremity of the spindle 50 abuts the end of the thimble 40 to limit the sliding movement of the rod 42 under the action of the spring 51. Through the above described arrangement the flattened portion of the rod 42 serves to hold the latter from turning in the arm 35 while allowing it to slide in the bore thereof. By turning the nut 53 on the end of the spindle 50 the rod 42 may be adjusted longitudinally of the arm 35 to set the burr-wheel 6 in proper relation to the needles 4. When once adjusted in this manner the burr or other appliance carried by the holder 12 is maintained in operative relation with the 70 needles 4 while being adapted to yield 80 when required through the compression of the spring 51.

It will be observed from the above description that my present invention provides a particularly simple and efficient mounting or holder for the various appliances or attachments employed on knitting-machines to cooperate with the knitting-needles. The annular track 10 provides a fixed mounting for the holders or standards which carry the appliances of the machine, and the slotted hubs of the holders 12 may be quickly attached or removed therefrom to adapt the machine for different classes of work. Through this arrangement the holders will 90 always be set in predetermined relation to the axis of the machine to render it more convenient to adjust the appliances radially in relation to the needles. Moreover, the 95 holders may be shifted in position circumferentially of the machine without disturbing the radial relation between the attachments and the row of needles. A further and most important feature of the improvement is the provision for setting a plurality 100 of holders, called a set, in close lateral relation whereby to allow the use of a greater number of attachments within a given space to increase the efficiency of the machine.

It has been explained that a single holder 105 is adapted to carry a plurality of attachments, such for instance as the burr-wheel and correlated presser-foot herein illustrated, and this arrangement results in a still further close grouping of the knitting 110 implements or attachments. The improved means for mounting the burr-wheels or other appliances on the holders also provides for greater compactness and simplicity 115 of structure while effecting a more rigid and 120 secure support therefor.

Various modifications may be made in the structure and arrangement of the parts of the apparatus without departing from the spirit or scope of the invention; therefore, without limiting myself to the exact embodiment herein disclosed, I claim:

1. In a knitting-machine, the combination 125 with the bed-plate and needle-cylinder thereof, of a laterally-slotted vertical post 130

adapted for adjustment on the bed-plate circumferentially of the needle-cylinder, a hollow arm provided with a hub surrounding the post, a rod slidable in the arm through 5 the slot in the post and having means engaging the sides of the slot to hold it from turning therein, means for mounting a knitting-implement at the end of the rod, and means for adjusting said rod longitudinally 10 of the arm.

2. In a knitting-machine, the combination with the bed-plate and needle-cylinder thereof, of a laterally-slotted vertical post adapted for adjustment on the bed-plate 15 circumferentially of the needle-cylinder, a hollow arm provided with a hub surrounding the post, a rod slidable in the arm through the slot in the post and formed with flattened portions engaging the sides of the 20 slot to hold it from turning therein, means for mounting a knitting-implement at the end of the rod, a spring for sliding the rod longitudinally of its axis, and adjustable means for limiting the movement of the rod 25 under the action of the spring.

3. In a knitting-machine, the combination with the bed-plate and needle-cylinder thereof, of a laterally-slotted vertical post adapted for adjustment on the bed-plate circumferentially of the needle-cylinder, a hollow arm provided with a hub surrounding the post, a rod slidable in the arm through 30 the slot in the post and formed with flattened portions engaging the sides of the slot 35 to hold it from turning therein, means for

mounting a knitting-implement at the end of the rod, a spring for sliding the rod longitudinally of its axis, and means adjustable on the rod to limit its sliding movement under the action of the spring. 40

4. In a knitting-machine, the combination of a vertical post formed with a lateral slot, an axially-bored arm provided with a hub attached to the post, a rod slidable in the bore of the arm and formed with flattened 45 sides engaging the slot in the post to hold it from turning therein, a spring in the bore of the arm acting on the rod to slide the latter, and means adjustable on the end of the rod to limit its sliding movement under the 50 action of the spring.

5. In a knitting-machine, the combination with the bed-plate thereof, of a ring secured thereto, a hub slotted at its base to straddle the sides of the ring and provided with a bore in its upper end, a laterally slotted cylindrical post seated in the bore in the hub to adapt it to turn therein, means for securing the hub to the ring, means for securing the post from turning in the hub, an arm 55 having a hub bored to adapt it to surround the post and provided with an axial bore of larger diameter than the slot in the post, a rod slidable in the axial bore of the arm and provided with an enlarged portion with 60 flattened sides engaging the sides of the slot in the post, and means for attaching a knitting-implement at the end of the rod. 65

In testimony whereof I affix my signature.
ADELARD FARLAND.
